CLAIM

The ornamental design for a golfing wrist control attachment or the like, as shown and described.

DESCRIPTION

FIG. 1 is a perspective view of a golfing wrist control attachment or the like embodying our new design, showing the top, front, and right side thereof;

FIG. 2 is a bottom plan view thereof, with the wrist straps shown only in their fastened position;

FIG. 3 is a front elevation thereof;

FIG. 4 is a rear elevation thereof.
